(57) **CLAIM**

The ornamental design for a thermometer as shown.

DESCRIPTION

FIG. 1 is an isometric view of a thermometer according to a first embodiment;

FIG. 2 is a side view of the thermometer illustrated in FIG. 1;

FIG. 3 is a side view, which is opposite the side view of FIG. 2, of the thermometer illustrated in FIG. 1;

FIG. 4 is a front side view of the thermometer illustrated in FIG. 1;

FIG. 5 is a rear side view of the thermometer illustrated in FIG. 1;

FIG. 6 is a top view of the thermometer illustrated in FIG. 1;

FIG. 7 is a bottom view of the thermometer illustrated in FIG. 1;

FIG. 8 is an isometric view of a thermometer in a first orientation according to a second embodiment;

FIG. 9 is a side view of the thermometer illustrated in FIG. 8;

FIG. 10 is a side view, which is opposite the side view of FIG. 9, of the thermometer illustrated in FIG. 8;

FIG. 11 is a front side view of the thermometer illustrated in FIG. 8;

FIG. 12 is a rear side view of the thermometer illustrated in FIG. 8;

FIG. 13 is a top view of the thermometer illustrated in FIG. 8;

FIG. 14 is a bottom view of the thermometer illustrated in FIG. 8;

FIG. 15 is an isometric view of a thermometer in a second orientation according to the second embodiment;

FIG. 16 is a side view of the thermometer illustrated in FIG. 15;

FIG. 17 is a side view, which is opposite the side view of FIG. 16, of the thermometer illustrated in FIG. 15;

FIG. 18 is a front side view of the thermometer illustrated in FIG. 15;

FIG. 19 is a rear side view of the thermometer illustrated in FIG. 15;

FIG. 20 is a top view of the thermometer illustrated in FIG. 15; and,

FIG. 21 is a bottom view of the thermometer illustrated in FIG. 15.

The broken lines in the drawings form no part of the design to be patented.
